UNITED STATES PATENT OFFICE.

GEORGE E. HAIGHT, OF MILFORD, AND WILLIAM H. WOOD, OF HARTFORD, CONNECTICUT, AND WILLIAM E. WINSOR, OF NEW YORK, N. Y., AS-SIGNORS TO JOHN N. H. PATRICK, OF NEW YORK, N. Y.

MEANS FOR HEATING AND CONTROLLING GASES FOR MOTORS.

SPECIFICATION forming part of Letters Patent No. 292,428, dated January 22, 1884.

Application filed August 31, 1883. (No model.) Patented in France September 25, 1883; in Belgium September 25, 1883; in Germany September 26, 1883; in Spain September 28, 1883; in Italy September 29, 1883, No. 15,925, and in England October 8, 1883, No. 4,776.

To all whom it may concern:

Be it known that we, GEO. E. HAIGHT, of Milford, Connecticut, WM. H. WOOD, of Hartford, Connecticut, and WM. E. WINSOR, of New York, N. Y., have invented certain new and useful Improvements in Means for Heating and Controlling Gases for Motors, of which the following is a specification, reference being had therein to the accompanying drawings.

- 10 This invention relates to the method of heating the gas to produce expansion for use in the class of motors which are driven by the expansion of compressed gas under high pressure, as carbonic-acid-gas engines and others 15 of that class, and is especially intended for use in gas-engines for torpedo-boats; also, to details of construction of the devices used for such engines, especially the gas-supply therefor.
- 20 The object of our invention is to produce a rapid expansion of the gas after it leaves the flask or holder, where it is held in a compressed or liquefied state, and before it enters the engine, and to prevent refrigeration, due to such 25 expansion.

The special features of our invention will be hereinafter pointed out in the claims.

In the drawings, Figure 1 is a longitudinal section of the shell of a torpedo-boat, showing 30 in a general way the arrangement of the parts or compartments of the boat. Fig. 2 is a longitudinal section of cylinder which contains the expansion-coils and chemicals. Fig. 3 is a cross-section thereof. Fig. 4 is a plan view 35 of the lime-chamber. Fig. 5 is an end view of the expansion-cylinder; showing device for dumping the lime-chamber. Fig. 6 shows the cover, and Fig. 7 its mode of attachment enlarged.

40 In Fig. 1, A is a flask or chamber in a torpedo-boat, adapted to contain carbonic acid, nitrous oxide, or similar gases. The pipe which conveys the gas from the reservoir to the engine passes through compartment B, over the 45 top of the expansion-cylinder to the throttle-valve S, then returns, and is passed back and forth in the cylinder b, then out to the engine in compartment D. The reel of cable by which

the boat is guided is in the compartment C. We give this as a convenient and desirable arrangement of the parts and compartments of the boat referred to; but other arrangements may be made.

The cylinder b—preferably of copper—is somewhat smaller in diameter than the compartment B of the boat in which it is placed, so as to leave room above said cylinder or flask for the passage of pipes and wires. In the lower portion of cylinder b the pipe a is coiled or stored, having a sufficient number of turns 55 to bring a considerable amount of surface in contact with any liquid which may be put in the vessel b. The cylinder b is partly filled with a mixture of sulphuric acid and water, which can remain for a considerable time in 60 contact with the pipe without special damage thereto. Other acid and alkaline agents than those herein mentioned may be used.

Above the coiled pipes a there is a lime-chamber, c. This lime-chamber is preferably 70 a trough having journals at each end, which journals pass through the heads d of the cylinder b. The trough, a side view of which is shown in Fig. 2, may be a pipe with a section or side removed.

The journal e has a gear-wheel, f, attached thereto, which engages with a worm, g, the shaft h of which leads to the outside of the boat, where it may be turned by a key or crank, thus revolving the chamber or trough 80 e in its bearings. The open portion of the trough e is covered, preferably, by a sheet of rubber, c', which is strengthened at the edges by wires c''. When the trough is filled with lime, the cover c' is cemented thereon to retain 85 the lime in place. The edge c'' of the cover c' is connected with the shell of the cylinder b by wires or chains i, which may be attached to hooks or rings K inside said reservoir. Thus when the lime-chamber is revolved on 90 its axis the cover c', being retained by said connections, will be torn off from the trough or chamber, and the contents of said chamber will be dumped.

The operation of our device is as follows: 95 The gas-reservoir being charged with gas,

and the expanding cylinder *c* being partly filled with liquid chemicals, so as to cover pipe *a*, and the lime-chamber being filled with lime hermetically sealed therein by the cover, when it is desired to start the boat, the rod *h* is turned, thus tearing off the cover of lime-chamber *c*, and dumping the lime into the chemicals at the bottom of the cylinder. By the rapid slaking of the lime a high degree of heat is at once developed. The gas flows from the flask to the throttle-valve, then through *a*, where it absorbs the heat developed by the chemicals in contact with the coils of pipe *a*, and is rapidly expanded and all danger of refrigeration avoided. The gas at once passes to the engines to propel the boat, and then escapes through the exhaust, or is condensed by suitable apparatus.

We claim—

- 20 1. The method herein described of expanding the gas in a supply-pipe, which consists in bringing a supply of lime suddenly into contact with a body of chemicals of the character described, said chemicals being in contact 25 with the feed-pipe leading to the engine, as set forth.
2. The combination of the expansion-chamber, the pipes therein, and the lime-chamber,

arranged as described, so that the lime-chamber may suddenly dump its contents into the 30 expansion-chamber, as set forth.

3. The combination of the flask, a pipe leading to the engine, an expansion - cylinder, through which said pipe passes, and a throttle-valve arranged between the flask or reservoir and the expansion-cylinder. 35

4. The combination, with the reversible lime-chamber, of the cover secured thereto, and devices, substantially as described, for tearing off the cover when the chamber is reversed. 40

5. The combination of the cylinder *b*, having pipes therein, as described, the lime-chamber *c*, having a cover, devices for removing said cover, and the worm-gear and shaft 45 leading to the exterior of the boat, for reversing the lime-chamber, as set forth.

In testimony whereof we affix our signatures in presence of two witnesses.

GEORGE E. HAIGHT.
WILLIAM H. WOOD.
WILLIAM E. WINSOR.
